UNITED STATES PATENT OFFICE.

PAUL T. ZIZINIA, OF NEW YORK, N. Y.

HICKEY.

1,080,616.

Specification of Letters Patent.

Patented Dec. 9, 1913.

Application filed March 28, 1913. Serial No. 757,279.

To all whom it may concern:

Be it known that I, PAUL T. ZIZINIA, a citizen of the United States, residing at 225 West Eightieth street, in the borough of 5 Manhattan, in the county of New York, city and State of New York, have invented certain new and useful Improvements in Hick- eys, of which the following is a specification.

This invention relates to hickies used to 10 connect an insulating joint to an electrolier or similar fixture, and its novelty consists in the construction and adaptation of the parts as will be hereinafter more fully pointed out.

15 As is well known to those skilled in the art to which this invention relates, because of the obligatory interposition of an insulating member to prevent the carrying of a short circuit into the building, thereby causing 20 danger of a conflagration, the usual electric light assemblage consists of a projecting stud which may be a gas pipe, an insulating joint, a hickey and a wire conduit, all assembled in line in the order named, and usually 25 connected together by threaded joints forming a continuous assemblage. The hickey in such combination is a small tubular device provided with holes or slots in its side or sides to permit of the wires which 30 are carried in the interior of the conduit to pass the insulating joint.

The hickey in common use to-day, so far as the same is known to me, is made with a substantially continuous vertical bore from 35 end to end, and is provided with an unsplit opening or openings in its side or sides. To assemble the combination, the wires projecting from the conduit are passed in at one end and out at the other end, going com- 40 pletely through the hickey which is then screwed onto the conduit. In order to withdraw the wires from a hickey of this kind, so that connection can be made with the insulating joint, it is necessary, by means of a 45 hook or similar tool, to fish the wires out through the side openings of the hickey. This is where a difficulty arises and frequently results in stripping the insulation from the wires, thereby necessitating an- 50 other wiring of the fixture. In order to overcome this difficulty, forms of the old hickey were devised in which slots were cut extending from one of its ends to a side opening, thereby permitting the wires, after 55 having been passed through the hickey, to be bent back through the slot or slots and

spread outward in the side openings, thus avoiding the necessity of fishing the wires out through the side openings. But by thus slitting the hickey, the device was weakened 60 to such an extent that reinforcement became necessary. Such reinforcement of the weakened hickey has been attempted by various devices, principally by detachable members such as interior plugs or exterior encircling 65 rings of special construction, all of which have added to the cost and the difficulty of assembling the parts without in reality adequately accomplishing the desired end. Be- 70 cause of the long leverage incident to the length of chandeliers and electroliers, any unnecessary weakening of the connecting joints cannot safely be permitted, and it has long been desirable to provide a hickey 75 which would have the advantage of permit- 80 ting the wires to be drawn out through the side openings without difficulty and which, at the same time, would not be weakened by the presence of slits or slots as in the construction above outlined.

It is the purpose of this invention to pro- 85 vide such a hickey by the use of which the wires are readily drawn from the connected fixture through the body of the hickey to the outside, one which needs no slotting or subsequent reinforcement, and which is simple, cheap, efficient and easy to use.

In the drawings, Figure 1 is a front eleva- 90 tion of an electric light assemblage including a hickey embodying the invention; Fig. 2 is a side elevation of the hickey separated from the other parts; Fig. 3 is a vertical central section through the hickey on the plane of the line 3-3 in Fig. 2; Fig. 4 is a front elevation of an electric light assem- 95 blage including a hickey having two side openings; Fig. 5 is a side elevation of the parts shown in Fig. 4; Fig. 6 is a central vertical section of a modified form of hickey with its side openings gradually diminish- 100 ing in cross sectional area; Fig. 7 is a central vertical section of a modified form of hickey showing its bottom opening expanded and threaded to permit of its connection with two wire conduits of different external di- 105 ameters; and Fig. 8 is a central vertical sec- 110 tion of another modified form showing a swivel interiorly threaded and secured to the hickey, thus providing a loose or rota- table connection to the wire conduit.

In the drawings, 10 represents the body of the hickey which is preferably made cy-

lindrical, frusto-conical or tubular in form, and which may be made of any suitable material as cast metal. The body of whatever shape is closed at the top and provided with means for connecting it to the usual insulating joint indicated at 20, and which means, in the form of the hickey illustrated, comprises a restricted externally threaded neck 11, the lower portion of the insulating joint 10 being provided with a threaded aperture to engage the threads of said neck. The body 10 is provided with a bottom opening indicated at 12 and a side opening indicated at 13, between which there is provided a passageway or bore 14 for the wires. In the bottom opening, the bore or passageway is preferably internally threaded to afford means for connecting the same to an upwardly extending and externally threaded 20 end of the wire conduit or similar fixture 30.

In use, the wires are readily passed through the bottom aperture 12 and guided out or deflected through the side openings 13 by contact with the walls of the passageway 14. This operation requires no thought or care, does not require the use of a tool, and is quickly performed.

It will, of course, be understood that the hickey may be provided with any usual suitable means whereby it may be connected with the wire conduit and the insulating joint, and that I am not confining myself to the use of an externally threaded neck or internally threaded aperture for the purpose 30 of making these connections, as any connections which perform an equivalent function will be within the principle of the invention.

In Figs. 4 and 5, there is shown a hickey in which there are two side openings allow-

ing the wires to be projected one through 40 each opening and in opposite directions.

In Fig. 6 the passageway is shown as provided with converging sides leading to each side opening so that its cross sectional area gradually diminishes from the center of the 45 hickey toward the side opening.

In Fig. 7 there is shown a modified form of the hickey, in which the lower part of the bottom aperture is expanded and threaded as indicated at 15, in order to provide 50 means by which wire conduits of different diameters may be joined to the same hickey, and in Fig. 8 there is shown a hickey provided with an external annulus 16 internally threaded as indicated at 17 and swiveled to 55 a shoulder 18 internally provided at the bottom of the hickey. This allows a threaded connection to be made with the wire conduit so that it can be rotated if necessary, and prevents the twisting of the wires if such 60 should occur.

What I claim is:

The combination with an insulating joint having a lower and internally threaded socket, of a hickey comprising a tubular 65 body having a closed top and an open lower end, an upstanding externally threaded neck projecting from the closed top and threaded into the socket of the insulating joint, said body having an opening through one side, 70 and a fixture element threaded into the lower end of the body.

In testimony whereof I affix my signature in presence of two witnesses.

PAUL T. ZIZINIA.
